(57) **CLAIM**

The ornamental design for a vehicle wheel rim, as shown and described.

DESCRIPTION

The patent or application file contains at least one drawing executed in color. Copies of this patent or patent application publication with color drawing(s) will be provided by the Office upon request and payment of the necessary fee.

1. Vehicle wheel rim

1.1 : Top

1.2 : Bottom

1.3 : Left

1.4 : Right

1.5 : Perspective

1.6 : Perspective

The reflections on the reproductions 1.1-1.6 of the wheel rim do not form part of the claimed design and are caused by the material and/or painting of the wheel rim; reproduction 1.1 is a front view of an automotive vehicle wheel rim showing the new design; reproduction 1.2 is a rear view of the automotive vehicle wheel rim; reproduction 1.3 is a view from the left side of the automotive vehicle wheel rim; reproduction 1.4 is a view from the right side of the automotive vehicle wheel rim; reproduction 1.5 is a perspective front view the automotive vehicle wheel rim; reproduction 1.6 is another perspective front view of the automotive vehicle wheel rim.
